COMBINED MOBILE HOME PORCH AND STEPS

John Richardson, P.O. Box 291, Shattuck, Okla. 73858

Filed June 1, 1973, Ser. No. 366,196

Term of patent 14 years

Int. Cl. D25—02

U.S. Cl. D13—7 R

FIG. 1

FIG. 2

FIG. 2

FIG. 1 is a front elevation view showing a combined mobile home porch and steps of the present invention, and illustrating in dashed lines, a mobile home with which the porch and steps can be used.

FIG. 2 is a side elevation view showing one side of a combined mobile home porch and steps opposite the side of the structure where the steps are located, and illustrating in dashed lines, a portion of a mobile home with which the porch and steps can be used.

FIG. 3 is a top plan view of the combined mobile home porch and steps of the present invention, and illustrating in dashed lines, a portion of a mobile home with which the porch and steps can be used.

FIG. 4 is a rear elevation view showing the side of a combined mobile home porch and steps of this invention which is opposite the side of the structure shown in FIG. 1.

FIG. 5 is a bottom plan view of a combined mobile home porch and steps of the present invention.

FIG. 6 is a side elevation view showing the side of a combined mobile home porch and steps upon which the steps are elevated.

The dash lines in the several views are for illustrative purposes only and form no part of the claimed design.

I claim:

The ornamental design for a combined mobile home porch and steps, substantially as shown and described.
